FUEL PUMP

Horace P. Miller, Oakland, Calif.

Application November 5, 1943, Serial No. 509,103

3 Claims. (Cl. 103—37)

1

My invention relates to pumps and particularly to high pressure fuel pumps.

Among the objects of my invention is the provision of a high pressure pump with accurately timed delivery, and capable of being operated at very high speeds. Another object is the provision of a high pressure pump in which the pressure on the fuel remains constant at a predetermined amount. Still another object is the provision of a fuel pump of the character described in which there are no ball check or poppet valves.

My invention possesses other objects and features of value, some of which, with the foregoing, will be set forth in the following description of the invention. It is to be understood that I do not limit myself to the showing made by the said description and the drawing, as I may adopt variant forms of the invention within the scope of the appended claims.

Referring to the drawing: Figure 1 is a vertical sectional view of a pump embodying my invention. The plane of section is indicated by the line 1—1 of Figure 2. Figure 2 is a side elevation of a four-unit pump.

In terms of broad inclusion each unit of my pump comprises a cylinder in one end of which a plunger is reciprocated by suitable connection to a power driven shaft. In the other end of the cylinder, a second plunger is pressed by an adjustable tension spring, and the penetration of the second plunger into the cylinder is controlled by an adjustable stop. By regulation of the spring tension the pressure on the fuel oil delivered by the pump is controlled; and by regulation of the adjustable stop, the quantity of fuel oil delivered with each pressure stroke of the power driven or pressure plunger is controlled.

The inner end of the pressure plunger is preferably recessed to provide a passage opening on the inner end of the plunger and also on its side; and the arrangement and proportion of parts is preferably such that when the plunger is at the low point of its stroke, fuel oil flows into the passage from an aligned feed port or passage in the wall of the cylinder and into the space between the ends of the two plungers, filling both space and passage.

At the top of its stroke the passage in the side of the plunger is in register with a fuel delivery port or passage at which time the oil caught between the two plungers is forced through the passage by the spring pressure on the second plunger. Because the entire periphery of the plungers seals off the feed and delivery ports, the parts do not require so close or accurate a fitting as in other

2

types of pressure pumps; and the efficient operating life of the mechanism without attention is almost limitless.

In greater detail, my invention as embodied in the structure shown in the accompanying drawing comprises a housing conveniently made in three parts—a cylinder block 2 in which four cylindrical bores 3 are formed, a crank case 4, in which is arranged the driving mechanism, including the driving shaft 6, preferably connected through the usual means to the engine shaft, and a hood 7 closing in the top. The three parts form a small, compact, closed assembly of four pump units, held together by screws 8.

Slidably disposed in the lower half of each cylinder is a piston, preferably a plunger 9, conveniently called a pressure plunger, and having a head 10 at its lower end, engaged in a T-slot in the cylindrical cross-head block 11 which is slidably in a cylindrical slideway 12, formed in the thickened upper wall 13 of the crank case 4. The lower end of the cross-head is slotted and a pivot pin 16 pivotally connects the cross-head to an eccentric 17, mounted on the eccentric disk 18, fixed on the drive shaft 6. The lower part of the eccentric extends into a body 19 of lubricant lying in the bottom of the case. The lubricant is introduced into the case, and checked through an opening normally closed by the plug 21, in the cover plate 22, forming a removable side wall for convenience in assembly of the four eccentrics and connected parts. In Figure 2, the four eccentric disks 18 are shown in dotted lines at low, high and intermediate positions, the four being spaced 90° apart, and the first one at the left of the figure being in its low position. In a 6 cylinder engine, the spacing between the eccentrics would be 60°.

The upper end of each pressure plunger 9 is formed with a passage opening on the end and on the side. Conveniently the passage is made by drilling a hole 26 axially in the end of the plunger to meet two transversely extending holes 27 at their intersection in the center of the plunger. The transverse holes at their outer ends terminate in the peripheral groove 28, so that there is a continuous passage, opening around the entire plunger side and on the end of the plunger. The parts are spaced and proportioned so that when the plunger is at the bottom of its stroke, as shown in Figure 1, the side opening 28 of the passage registers with a feed or delivery port 29, connecting the fuel supply passage 31 with the interior wall or face of the cylinder bore. This fuel supply passage 31 ex-

tends through the body of the cylinder block and supplies fuel to each of the pump units, either by gravity feed or by a gear pump interposed in the line.

The period of registration of the feed port and side opening of the passage is of course very brief, but in that instant, fuel from the supply passage flows through the plunger and out at the top end into whatever space 32 exists above the pressure plunger. This space or chamber 32 in the cylindrical bore immediately above the pressure plunger is the measure of the fuel charge to be forcibly injected into the associated engine cylinder; and means are provided for readily varying the volume of the chamber to correspondingly vary the fuel charge injected.

Slidably disposed in the upper portion of each cylinder is a plunger 36, conveniently termed a metering plunger, and having a head 37, resting upon the adjustable stop 38 which is preferably a cap threaded on a nipple 39, surrounding the plunger and extending upwardly from and forming part of the cylinder block. Rotation of the cap-stop obviously raises or lowers it and correspondingly determines the innermost position of the metering plunger and the size of the chamber 32. Means are provided for selective adjustment of the stop, so that the quantity of fuel injected into the engine cylinders may be controlled.

Formed on the outer cylindrical face of the cap are gear teeth 41, meshing with the teeth of the rack 42, arranged in a sideway formed in the hood 7, and connected to an operating or throttle lever by suitable linkage 43. Movement of the lever is effective through the rack to turn the cap in or out to reduce or increase the minimum volume of the chamber 32.

Means are provided for maintaining on the head 37 of the metering plunger, a substantially constant but adjustable resilient pressure. This is accomplished by interposing between the head and the housing hood 7 a coil spring 47, seated around the stud 48 on the head and on a similar stud and head 49 carried by the screw 51, threaded into the top of the head 7, and held by the lock nut 52. Adjustment of the screw in or out will of course vary the tension on the spring.

Formed in the cylinder block, preferably on the opposite side of each bore from the feed port is a fuel delivery passage 53, opening in a delivery port in the wall of the bore a short distance above the feed port. The delivery passage terminates at the outside of the cylinder block in a threaded aperture, in which the delivery pipe 54 leading to the engine cylinder is removably held. The spacing of the parts is such that the side opening 28 of the pressure plunger passage registers with the delivery port and passage 53 when the pressure plunger is at the top of its stroke.

With the chamber 32 filled with fuel, upward movement of the pressure plunger compresses the fuel against the metering plunger which then rises against the pressure of the spring 47, so that when the pressure plunger reaches the top of its stroke and the passage 28 registers with the delivery port, the oil in the chamber 32, under the force applied by the compressed spring, flows back through the passages 26-27-28 and 53 into the pipe 54 and thence to the engine cylinder.

It will be readily understood that while the several passages will remain full of oil after the operation has once been started, the amount of fuel oil injected into the engine cylinder will

be the exact amount forced out of the chamber 32 between the two plungers. It will also be clear that the cap 38 may be lowered to its extreme position in which the lower end of the metering plunger will touch the upper end of the pressure plunger at its high point, so that the volume of chamber 32 approaches zero. Under these conditions, the fuel oil will merely fill the plunger passages, but none will be injected into the delivery passage. At the other extreme of movement of the stop, the separation between the plunger ends, that is, the volume of chamber 32 is at the maximum and the maximum charge of fuel oil is injected. In all positions however between these extremes the pressure of the spring as adjusted by the set screw 51 is substantially the same, and the oil is injected under substantially constant pressure irrespective of the quantity handled, or variation in speed of the drive shaft 6 and pressure plungers.

An important feature of my invention is the fact that thoroughly efficient performance over a very long operating life is secured with operating parts, in the manufacture of which considerably wider tolerances are permitted than would normally obtain in mechanisms of this sort. A considerable amount of leakage past the plungers is expected and has to be taken care of. This is most easily done by providing a drain passage 61, extending from the upper face of the cylinder block under the cap into a recess 62, surrounding the pressure plunger on the under side of the block. A passage 63 connects this recess to the fuel tank. Both plungers of each pump unit, the cap-stops, the rack and cross-heads are lubricated by this fuel oil leakage.

I claim:

1. A fuel injection device comprising a cylinder, a pressure plunger in the cylinder, means for reciprocating the plunger through pressure and recovery strokes, a fuel passage in the plunger opening on its inner end and upon the side thereof in aligned feed and delivery ports, a fuel feed passage opening into the cylinder in register with the feed port of said plunger passage when the plunger is at the end of its recovery stroke, a fuel delivery passage opening into the cylinder in register with the delivery port of said plunger passage when the plunger is at the end of its pressure stroke, a metering plunger slideable in the cylinder, resilient means for pressing the metering plunger into the cylinder, and means for varying the inward limit of movement of the metering plunger.

2. A fuel injection device comprising a cylinder, a pressure plunger in the cylinder, means for reciprocating the plunger through pressure and recovery strokes, a fuel passage in the plunger opening on its inner end and upon the side thereof in aligned feed and delivery ports, a fuel feed passage opening into the cylinder in register with the feed port of said plunger passage when the plunger is at the end of its recovery stroke, a fuel delivery passage opening into the cylinder in register with the delivery port of said plunger passage when the plunger is at the end of its pressure stroke, a metering plunger slideable in the cylinder, resilient means for pressing the metering plunger into the cylinder, a stop for limiting the inward movement of the metering plunger, and means for varying the position of the stop.

3. A fuel injection device comprising a cylinder, a pressure plunger in the cylinder, means for re-

ciprecating the plunger through pressure and recovery strokes, a fuel passage in the plunger opening on its inner end and upon the side thereof in aligned feed and delivery ports, a fuel feed passage opening into the cylinder in register with the feed port of said plunger passage when the plunger is at the end of its recovery stroke, a fuel delivery passage opening into the cylinder in register with the delivery port of said plunger pas-

sage when the plunger is at the end of its pressure stroke, a metering plunger slidable in the cylinder, resilient means for pressing the metering plunger into the cylinder, a cap threaded on the cylinder and forming a stop for limiting the inward movement of the metering plunger, and means for rotating the cap to vary the position of the stop.

HORACE P. MILLER.
